UNITED STATES PATENT OFFICE.

HARRY N. LOWENTHAL, OF PHILADELPHIA, PENNSYLVANIA, ASSIGNOR TO BEAUMONT MANUFACTURING COMPANY, OF PHILADELPHIA, PENNSYLVANIA, A CORPORATION OF NEW JERSEY.

GATE FOR ASH HOPPERS.

Application filed May 23, 1922. Serial No. 563,141.

One object of my invention is to provide means for carrying away the water that is used in an ash hopper for quenching the ashes.

5 A further object of the invention is to provide the gate, which extends under the hopper, with gutters for collecting the water as it escapes from the hopper, the water being discharged into a suitable fixed 10 trough, or drain.

The invention also relates to certain details of construction, which will be fully described hereinafter, reference being had to the accompanying drawings.

15 Fig. 1 is a sectional view, taken approximately on the staggered line 1—1 of Fig. 2, and illustrating my improved ash hopper gate with said gate in position under the hopper.

20 Fig. 2 is a sectional plan view on the line 2—2, Fig. 1, showing the gate withdrawn from under the hopper.

Fig. 3 is a sectional view on the line 3—3, Fig. 1.

25 Fig. 4 is a sectional view of the gate on the line 4—4 Fig. 2.

Fig. 5 is a sectional view taken approximately on the line 5—5, Fig. 2 with the gate in position below the hopper, and,

30 Fig. 6 is a sectional view illustrating two gates under a single hopper.

Referring to the drawings, 1 is an ash hopper of the ordinary type. 2 is the base

35 ring of the hopper. 3 is the casing having a lining 4 of fire brick, in the present instance. The base ring 2 has a downwardly-extending wall 5 at each side, which each support one end of a rail 6. The rails 6 are secured to the extension walls 5 by bolts 7,

40 which also extend through spacing blocks 8, as shown in Fig. 3. The opposite ends of the rails 6 are supported by beams 9, which are secured to lateral brackets 10 integral with the extensions 5 of the base ring 2 and to a 45 suitable support 9 on a wall 11, or any other fixed part of a structure in which the ash hopper 1 is located.

50 12 is the gate of the hopper. This gate 12 is arranged to close the bottom, as shown clearly in Fig. 1, or to be moved to one side of the hopper 1, as illustrated in Fig. 2. The gate 12 is made in the form of a casting hav-

ing longitudinal ribs 13 and transverse ribs 14 forming pockets for fire bricks 15, which are arranged in said pockets, as shown clearly in Figs. 2 and 3, to form a substantial surface on which the ashes rest. The flanged wheels 16 are conveniently housed in pockets 17, with the trunnions thereof located in opposed recesses in the lower edges of the walls 18 of said pockets. Secured to the outer end of the gate 12 is a bracket 19 to which a piston rod 20 is coupled. This piston rod 20 is connected to a piston within a cylinder 21 supported by transverse beams 22 secured to the longitudinal beams 9 by angle bars 9', as shown clearly in Fig. 3, so that, when fluid under pressure is admitted to the forward end of the cylinder 20, the piston and the gate 12 to which it is connected are moved away from the hopper 1 in order that said gate will be drawn to one side of the hopper 1 when fully opened, as in Fig. 2, thereby allowing the contents of said hopper to be discharged into any suitable receptacle thereunder, or onto a floor, from which it is removed by any suitable means. When fluid is admitted to the opposite end of the cylinder 22, the gate 12 is moved to the closed position, as shown in Fig. 1. The base ring 2 of the hopper 1 is conveniently made in four sections, but it will be understood that it may be made in as many sections as desired, depending, somewhat, on the size of said hopper.

When an ash hopper is used, the ashes are usually quenched with water. This water is allowed to drip from the hopper 1, which is objectionable in many installations, especially where said hopper is arranged over a driveway. In order to collect the water that drains from the ashes, the gate 12 is provided with a gutter 22 at each side, which gutters are connected by a gutter 23 at the inner end of said gate. This gutter 23 gradually inclines downwardly from a high point at the center 24 towards the side gutters 22 so that, when the gate 12 is in position under the hopper 1, as in Figs. 1 and 3, the water escapes from under the base ring 2 in the direction of the arrows, Figs. 3 and 5, into the side gutters 22 and the end gutter 23. The outer walls 25 of the gutters 22, 23 are of a greater height than the upper sur-

face of the gate 12 so that any water splashing against each side walls will be directed into the gutters 22 and 23. The side gutters 22 discharge into a stationary trough 26 fixed 5 to the outer end of the hopper structure, while the water escaping at the front of the hopper 1 also discharges directly into the fixed trough 26, as shown by arrows, Fig. 5. The water can be carried away from the 10 trough 26 through a spout 27 to any convenient point.

It will be noticed that the side gutters 22 are on an incline, as denoted by dotted lines in Fig. 1, so that the water flows freely from the 15 transverse or end gutter 23 in opposed directions through the gutters 22 to the stationary trough 26.

In some types of hoppers, especially those of a larger size, it may be desirable to close 20 the bottom of the hopper with two or more gates.

In Fig. 6, two gates 12^a are illustrated, which close the bottom of the hopper 1^a. The base ring 2^a has a narrow central partition 28, 25 which is recessed to receive a row of fire brick 29. In addition to the side extensions 5^a, to which the rails 6^a are attached, a central extension 5^b depends from the partition 28 and rails 6^b are attached to this extension and are 30 supported on beams 9^b. The rails 6^a are supported on beams 9^a. Two cylinders 20^a are used for the two gates 12^a, said gates being operated in the same manner as a single gate. These two gates 12^a have gutters 22^a and 23^a, 35 not visible, similar to those illustrated in Fig. 1, for carrying off the water that escapes from the ashes in the hopper 1.

This construction makes the partition between the gates very narrow so that practi-

cally no ashes remain in the partition when 40 the gates are opened.

I claim:

1. The combination with a hopper of a base ring providing the discharge opening, said base ring having depending side walls 45 with integral end brackets, rails suspended by said brackets a gate embodying means to carry away drainage from the hopper while closing the discharge outlet thereof, said gate having open-bottom pockets at its underside 50 with axially aligned bearing recesses in the lower edges, wheels journalled in the recesses to co-operate with the rails aforesaid, and means operative to move the gate into and out of closed position.

2. The combination with a hopper of a base ring constituting the discharge opening, said base ring having integrally-formed parallel 60 depending side walls with lateral end brackets, rails suspended by said brackets and spaced from the bodies of the side walls, a gate including an open-ended gutter to carry off drainage from the hopper while closing the discharge outlet, the gutter embodying 65 downwardly inclined parallel portions with a connecting portion inclined thereto in opposed directions from a medial high-point, said gate embodying open-bottom pockets at its underside with axially aligned bearing recesses in the lower edges, wheels journalled in the recesses and engaging the rails aforesaid, means adapted to move the gate into 70 and out of closed position relative to the hopper, and a stationary trough sustained by the base ring to receive drainage from the 75 hopper as discharged by the open-ended gutter.

HARRY N. LOWENTHAL.
